UNITED STATES PATENT OFFICE.

ARTHUR J. CUMNOCK, OF RYE, NEW YORK.

WOVEN FABRIC.

1,071,143.

Specification of Letters Patent. Patented Aug. 26, 1913.

Application filed February 18, 1907. Serial No. 357,850.

To all whom it may concern:

Be it known that I, ARTHUR J. CUMNOCK, a citizen of the United States, and resident of Rye, New York, have invented 5 certain new and useful Improvements in Woven Fabrics, of which the following is a specification, accompanied by drawings.

This invention relates to woven fabrics, and the prime object of the invention is to 10 simplify and reduce the cost of manufacturing garments and other articles of woven fabric, having both top and bottom edges of dissimilar contour projecting beyond the inter-woven portion of the fabric.

15 Certain other objects are also accomplished, as will be apparent from the following description of the invention.

Further objects of the invention will hereinafter appear, and to these ends the 20 invention consists of a woven fabric for carrying out the above objects embodying the features of construction, combinations of elements and arrangement of parts substantially as hereinafter fully described and 25 claimed in the following specification and shown in the accompanying drawings, in which,

Figure 1 is a plan view of a portion of the fabric; Fig. 2 is a plan view of a portion 30 of a modification.

Referring to the drawings A represents the fabric, which in this instance is a tubular seamless woven fabric, comprising the layers B and C. The tubular fabric is provided with interwoven portions D therein shown in Fig. 1 woven transversely of the warp, while in Fig. 2 these interwoven portions are represented by E woven longitudinally of the warp. The interwoven 35 portions D or E are broken as indicated in the drawings instead of extending continuously as in my co-pending application, Serial No. 205,695, filed April 30, 1904, and one of the objects of breaking these 40 portions is to enable the collars or other articles of wearing apparel to be cut or otherwise formed out of the fabric around the broken interwoven portions so that each article 45 shall have an interwoven portion embedded therein.

50 Preferably the interwoven portions D or E lie end to end in substantially parallel

rows, and this is to facilitate the laying out of the articles to be cut.

In Fig. 1 collars are indicated in dotted 55 lines F, each collar being outlined around an interwoven portion D, and as shown, the interwoven areas are preferably arranged to form portions of the collar bands. In order to save material and prevent waste 60 the outlines of the collars are preferably nested as indicated in Fig. 1, and in order that this may be better accomplished the interwoven portions D are staggered as shown.

65 A main feature of the invention consists in so weaving the fabric that the article having upper and lower edges of dissimilar contour may be formed therefrom and to that end the interwoven parts are spaced in 70 such manner that the upper part of one article, such as a collar, and the lower part of another, and additional article of the same kind, can be formed from the portions between the interwoven parts. For instance, as seen in Fig. 1, it is apparent that 75 the inter-woven portions are so spaced that between said rows of inter-woven portions it is possible to have parts of two different collars to-wit the upper fold of one collar 80 and the lower fold of a second collar, and the upper edges of the collars being of dissimilar contour from the lower edges the fabric plainly adapts itself in a highly advantageous way to the forming of the collars with a minimum waste of material and 85 a minimum amount of labor.

85 In Fig. 2 the interwoven portions E are preferably formed unstaggered and extending in straight lines while the outlines of 90 the collars are not nested as in Fig. 1, and this arrangement is designed to facilitate the cutting of the collars.

95 I claim and desire to obtain by Letters Patent the following:

1. As a new article of manufacture, a collar fabric having a band portion formed by interwoven portions of the upper and lower layers of said fabric, the upper and lower layers projecting beyond the interwoven 100 portions both above and below the interwoven portion and also at the ends of the interwoven portions, substantially as specified.

2. As a new article of manufacture, a collar fabric having a band formed by inter-weaving a portion of two layers of fabric, said layers of fabric projecting both above and below the solid webbing band portion for forming the fold and also the attaching portions of the collar, substantially as specified.

In testimony whereof I have signed this specification in the presence of two subscribing witnesses.

ARTHUR J. CUMNOCK.
